UNITED STATES PATENT OFFICE.

LEWIS GEORGE TANDY, OF NEW YORK, N. Y.

LOCOMOTIVE.

Application filed May 18, 1923. Serial No. 629,730.

To all whom it may concern:

Be it known that I, LEWIS GEORGE TANDY, a citizen of the United States, residing at New York, in the county of New York and State of New York, have invented certain new and useful Improvements in Locomotives, of which the following is a specification.

This invention relates to locomotives and railway vehicles and has special reference to weight-transmitting bearer devices, the invention being particularly useful in connection with locomotives having a main frame primarily supporting the locomotive boiler, and a supplemental frame, articulated to and extending rearwardly of the main frame, beneath the boiler or fire box and adapted to transmit pulling and buffing strains.

One of the primary objects of my invention is to provide an arrangement for transmitting weight which permits relative movement of the articulated frame with respect to the fire box end of the boiler during curving, offering resistance to such lateral motion for centering purposes, and for providing lateral stability to prevent vibrating, and compensating for the difference in the longitudinal expansion of the boiler with respect to the articulated frame.

More specifically, my invention contemplates a combined bearer and lateral motion device, making provision for longitudinal expansion of the boiler.

In addition, my invention has to do with certain novel features and details of construction hereinafter more fully pointed out.

The foregoing, together with such other objects as may hereinafter appear, or are incident to my invention, I obtain by means of a construction which I have illustrated in preferred form in the accompanying drawings, wherein:

Fig. 1 is a diagrammatic side elevation of a locomotive illustrating the application of my improvements;

Fig. 2 is a fragmentary rear end elevation of Fig. 1, drawn on an enlarged scale to more clearly illustrate the parts;

Fig. 3 is a horizontal section through a

detail of my improvements, drawn on an enlarged scale, the section being taken on the line 3—3 of Fig. 4; and

Fig. 4 is an end elevation of Fig. 3.

Referring now to the drawings, and particularly Fig. 1, the reference letter A designates the boiler of the locomotive, such boiler having the usual fire box 7 and cab 8, it being understood for the purposes of this specification that the term boiler generally includes the superstructure of a locomotive. At the front end, the boiler is rigidly attached to the usual cylinder or saddle castings 9, the cylinder and saddle castings in turn being secured to the main frame 10 carrying the drivers 11. The boiler, at spaced intervals, is supported on the main frame by means of the expansion bearers 12 which permit the boiler to expand longitudinally relative to the main frame. The forward end of the fire box 7 is similarly supported by an expansion bearer 13. In the particular locomotive shown, the main frame terminates, at the rear, at a point approximately in the plane of the juncture between the boiler proper and the fire box, and articulated to this main frame and extending rearwardly thereof is a supplemental frame 14 which extends beneath the fire box 7 and is provided with two axles, 15 and 16, having wheels, 17 and 18. The side members of the supplemental frame, as will be clear on inspection of Fig. 2, are in a plane outside the plane of the wheels 17 and 18, and at the rear, the supplemental frame is provided with a foot plate 19 for draft connection with the tender, not shown. It is to be understood that my invention, while particularly useful in connection with this form of supplemental articulated frame, may be useful in connection with other forms of trailing frames.

Attention is now directed to the bearer device for transmitting weight to the articulated frame. The bearer includes what may be termed a main member B extending transversely of the fire box and the supplemental frame and having at its ends, housing portions 20, flanged, as at 21, for attachment to an adjacent part of the fire box,

such for example, as to the castings 22 which in turn are secured to the mud ring 23 of the fire box. The housing portions are box-like in character, open at the bottom. Within each housing is a box-like member 24 in which a lateral motion rocker or roller 25 is journaled. The boxes 24 are of such dimension that they will slide within their housings in a longitudinal direction; i. e., in a direction longitudinal of the locomotive, but they are supported against lateral displacement relative to the housings. The housings and the boxes are provided with pads 26 and 27 at the corners, which pads are machined so as to provide faces on which sliding movement of the boxes can take place. By virtue of this arrangement there is a floating relation between the main member of the bearer and the boxes. One of the purposes of this construction is that, as expansion of the boiler takes place when the locomotive is fired up, the main member of the bearer is free to move toward the rear.

The rollers or rockers 25 are tangent to the circle described by the articulated frame when it swings laterally about its pivot point 28 in the main frame, as a center. These rockers are designed so as to offer resistance to lateral motion during curving and they rest upon the upper faces of the side members of the articulated frame, as will be clear on inspection of Fig. 2.

The weight carried by the articulated frame is transmitted from the main member of the bearer to the boxes 24 by means of the links or keys 29, the ends of which are rounded and seated in the socket-like seats 30 and 31 respectively formed on the housings and the boxes 24.

It will be observed that when lateral or swinging motion of the articulated frame takes place, the rolling movement of the rockers results in a displacement of the boxes 24 longitudinally of the locomotive by the difference between the straight line tangent and arc. This displacement must occur freely, that is, without undue friction, and the link construction permits the boxes to adjust their position readily as lateral motion takes place. Thus, during curving, the boxes float with respect to the main member; and on expansion of the boiler, the main member is free to float or shift with respect to the boxes.

The links will not fall off for, although the sockets or seats 31 are open at one side, the seats 30 are closed on both sides.

What I claim is:

1. In a locomotive, the combination of a main frame, a boiler rigidly supported thereby, a weight carrying frame articulated to the main frame, and a weight transmitting means between the articulated frame and that portion of the boiler supported thereby permitting relative lateral move-

ment of the articulated frame and compensating for expansion of the boiler longitudinally thereof.

2. In a locomotive, the combination of a main frame, a boiler rigidly supported toward one end on the frame, expansion bearings for the boiler, a frame articulated to the main frame and carrying part of the weight of the boiler, and expansion bearer means between such articulated frame and the boiler.

3. In a locomotive, the combination of a main frame, a boiler rigidly supported toward one end on the frame, expansion bearings for the boiler, a frame articulated to the main frame and carrying part of the weight of the boiler, and expansion bearer means between such articulated frame and the boiler, said articulated frame having lateral movement relative to the boiler.

4. In a locomotive, the combination of a main frame, a boiler primarily supported thereby, a frame articulated to the main frame and supporting part of the weight of the boiler, and a combined expansion bearer and lateral motion resisting device between the boiler and the articulated frame.

5. A weight transmitting bearer device for railway vehicles including a housing, a box therein having relative movement of translation with respect thereto, and lateral motion resisting means carried by the box.

6. A weight transmitting bearer device for railway vehicles including a housing, a box therein having relative movement of translation with respect thereto, and a lateral motion resisting rocker carried by the box.

7. A weight transmitting bearer device for railway vehicles including a housing, a box therein having relative movement of translation with respect thereto, and a centering rocker carried by the box.

8. A weight transmitting bearer device for railway vehicles including a housing, and a lateral motion permitting means carried thereby with capacity for movement in a direction generally transverse the line of lateral movement.

9. A weight transmitting bearer device for railway vehicles including a housing, a box therein having relative movement of translation with respect thereto, and a weight transmitting link between housing and box.

10. A weight transmitting bearer device for railway vehicles including a housing, a box therein having relative movement of translation with respect thereto, and a weight transmitting link between housing and box, together with lateral motion means carried by the box.

11. A weight transmitting bearer device for railway vehicles including two members,

one of which is floating relative to the other, rocker to move in a substantially straight line as the truck swings.

12. A weight transmitting bearer device for railway vehicles including a main member, a pair of spaced members having floating relation therewith, and a lateral motion resisting means on each floating member.

13. In a centering device for a radial or swinging truck, a rocker set tangent to the arc of the truck, and means permitting the

14. A weight transmitting bearer device for railway vehicles including a housing means and a lateral motion means carried thereby, one of said means having capacity for movement in a direction generally transverse the line of lateral movement.

In testimony whereof, I have hereunto signed my name.

L. GEORGE TANDY.
